WALTER J. TIDD, OF SPRINGFIELD, MASSACHUSETTS, ASSIGNOR TO TIDD RECORDING CLOCK COMPANY, OF SPRINGFIELD, MASSACHUSETTS, A CORPORATION OF MASSACHUSETTS.

WATCHMAN'S RECORDING DEVICE.

1,283,361.

Specification of Letters Patent. Patented Oct. 29, 1918.

Application filed January 16, 1917. Serial No. 142,625.

To all whom it may concern:

Be it known that I, WALTER J. TIDD, of the city of Springfield, county of Hampden, and State of Massachusetts, have invented certain new and useful Improvements in 5 Watchmen's Recording Devices, of which the following is a specification.

This invention relates to improvements in 10 watchmen's recording devices which are used in such establishments as manufacturing plants or department stores, where the 15 watchman is required to make regular inspection trips about the building. These devices are usually located at convenient points about the buildings, and as the watchman goes the rounds he is required to register the time that he makes the different trips.

An object of the invention is to provide a 20 device that will accurately record the time that these trips are made and one that cannot be tampered with without showing that unauthorized parties have interfered with the proper workings of the device.

The invention, broadly, comprises a casing 25 adapted to be rigidly attached to a fixed support. Located within the casing is a clock of suitable construction. Operable by the clock train is a suitable disk of paper that is graduated into twenty four equal 30 parts to represent the hours in a day. Located adjacent this disk is a perforating device for engaging the edge of the paper for indicating the time the inspection trips are made.

35 A further object of the invention is to provide a suitable locking means for holding the casing closed during a certain period of time during the twenty four hours and at the end of that period permitting the same 40 to be opened and the disk of paper removed. Another object of the invention is to provide suitable means for securing the dial to the operative part of the clock.

Referring to the drawings:

45 Figure 1 is an end elevational view showing the outside of the casing, which contains the clock movement, the casing being attached to a fixed support; the perforating knob on the exterior part of the casing is illustrated and also the usual winding key; 50 Fig. 2 is a plan view of Fig. 1 showing the casing open and illustrating the graduated dial, the spring device for removably securing the dial in place and the movable disk

having a cut out portion for permitting the 55 casing to be locked and unlocked to its fixed support;

Fig. 3 is a vertical sectional view taken on the line 3—3 of Fig. 1 looking in the direction of the arrows and conventionally showing the supporting frame for the movement in outline and the spring actuated perforating device in full lines, the dial in end elevation and the operating means by which the dial is rotated, and the locking means for retaining the casing closed and for permitting it to be opened at stated intervals;

Fig. 4 is a side elevational view of a modification for retaining the casing locked to its support; 70

Fig. 5 is a front elevational view of the construction shown in Fig. 4; and

Fig. 6 is a detail view of the dial retaining spring; and

Fig. 7 is a detail sectional view showing 75 the perforating point passing through the graduated disk.

Referring to the drawings in detail, the casing in which the clock movement is contained is indicated at 1 and is preferably 80 cup-shaped in cross section, as shown in Fig. 3. This casing is suitably secured to a fixed support 2 by means of the hinge joint 3. Located within and secured to this casing is the usual clock-movement, the frame 85 portion only of which is conventionally indicated by the numeral 4. It should be noticed that the face end of the clock is turned toward a fixed support 2 for the purpose of leaving the outer end of the casing free from 90 obstructions and to prevent unauthorized persons from interfering with the clock movement. The usual hour-post of the movement is indicated at 5. Operated from this post by means of the pinion 6 is a gear 95 7 which carries a pinion 8. This pinion drives the gears 9 and 10. The gear 9 has secured thereto a disk 11 having a cut-out portion 12 of suitable length. The gear 10 has secured thereto the disk 13 which in 100 turn carries the graduated dial 14 which is suitably secured to the post 5 by means of the spring clip 15 having the opening 16. The post 5 carries a pin 17 which passes through the opening 16. 18 is the usual collar on the hour post. The cut out portion 12 in the disk 11 is for the purpose of permitting the post 19, having the downturned end

20, to pass therethrough. 21 designates a ring that is secured to the clock frame 4 by means of the brackets 22. 23 is a projection on the clip which serves as a handle means 5 for placing the clip on the post, whereby the graduated dial is held in place. Mounted in the frame of the clock and between the side plates thereof is a spring actuated rod or perforating device 24 which is provided 10 with a disk part 25 at its outer end. Located between the side plates of the clock is an expansion spring 26 which normally holds the perforating device 24 outward in its inoperative position. The graduated dial 14 passes 15 through the fixed ring 21 and the perforated plate 27 which serves as a guide for the end of the perforator and prevents the graduated paper disk or dial from being torn. The perforator 24 is disengaged from the 20 dial of course by the ring 21 as the perforator returns. The perforating rod 24 passes through an opening 21' in the ring 21 as shown in the detail view in Fig. 7.

It will be observed that when the cut-out 25 portion 12 of the disk 11 is opposite the down-turned end 20 of the bracket 19 that the casing 1 can be opened or closed, but as the clock train moves this disk forward that part of the disk which is not cut out will 30 pass behind the part 20 of the bracket and hold the casing permanently closed until the clock has run for a definite period, as for example twenty-two hours. The cut-out portion 12 represents a definite length or 35 period, as two hours, and during this period that the cut-out portion is opposite the part 20 access can be had to the interior of the casing for the purpose of inspecting the dial 14 or for removing the same and putting 40 a new one in place. It will be observed that the edge of the dial 14 is formed with suitable graduations or division marks between the hours, as indicated at 28. The perforating device 24 is to be understood as perforating the paper on the median lines 29 whereby by the time of perforation of the dial made 45 by the watchman can be determined within a very few minutes by means of the fine graduations 28.

50 Referring now to the modifications shown in Figs. 4 and 5. In place of the disk 11 having the cut-out portion 12, a lever 30 is pivoted to the frame 4 at 30'. This lever is actuated by a cam 31 on the disk 13. A 55 spring 32 normally holds the lever 30 against the pin or stop 33. The outer end of the lever 30, when in locking position, engages a slot 34 in the post 35 and when in unlocking position as shown in Fig. 5 it engages 60 the cam 31 which holds it in the position shown in this figure, whereby the casing 1 can be opened. The ring 21 is formed with an opening 21' to permit the bracket 19 or post 35 to pass. From this construction it

will be seen that I have provided a locking 65 device for a watchman's time clock that cannot be tampered with during the hours that the watchman should perform his duties, and that after these duties have been performed the clock casing is automatically un- 70 locked and will permit the proper person to have access to the interior of the casing for the purpose of inspection and renewal of the graduated dial 14 as already stated. 36 designates a spring latch which engages a 75 pin 37 in the upper side of the casing 1 and when the outer end of this latch is raised the casing 1 can be tipped forward in the position 80 shown in Fig. 2 for inspection and access.

It will be observed that the dial carrying disk 13 is located within the ring member 21. It will also be observed that the ring member 21 is located adjacent the inner or open end of the one-piece inclosing casing 1 85 and adjacent the inner surface of the same. The present improvement embodies the idea of simplicity, in that the mechanism is all contained in a one piece inclosing casing. 90

What I claim is:

1. In a watchman's time recording device, the combination with an inclosing casing, means for pivotally attaching the same to a fixed support, said casing being cup-shaped and turned toward the fixed support, 95 a clock movement located within the casing, a graduated dial operated by the movement, means comprising a perforating device mounted in and passing through the frame of the clock and its inclosing casing to the outer 100 rear side for operation at that side of the casing, and adapted to engage the outer edge of the dial for registering the time that the perforating device is operated.

2. In a time recording device, means for 105 securing a graduated dial to the clock train and comprising a flat, one-piece bowed spring clip formed with an opening there-through to receive the hour post of the clock movement, and to permit the hour post and 110 a pin on the hour post to pass through the opening in the clip, whereby when the clip is turned to a position so that the opening in the clip is out of register with the post and its pin, a dial will be clamped to the clock 115 train.

3. A watchman's time recorder comprising, in combination with the movement of the clock, an inclosing casing having one 120 end closed and the other end open, the open end being turned toward a fixed support, a pinion driven from the movement, a disk driven from the pinion and having a graduated dial secured directly thereto, and a perforating device consisting of a single rod 125 operable from the outer closed end of the inclosing casing for engaging the said dial, said perforating device being located in and

passing through the frame of the clock and through the rear wall of the casing and extending to the outer closed end of the casing.

4. A watchman's time recorder comprising in combination with a one piece inclosing cup shaped casing to contain a suitable clock movement, the open end of the casing being turned toward a fixed support, a rotatable disk driven from the movement, a graduated disk carried by the clock train and passing in front of a plate with an opening, said plate being spaced from said disk and to which the graduated disk is secured, a perforating pin, or device, slidably mounted in and passing completely through the frame of the clock movement and the casing and extending through the outer rear side of the casing to permit its being operated at that point for perforating the disk, said perforated plate serving to receive the point of said pin and to disengage the graduated disk from the pin after being perforated.

5. A watchman's time recorder comprising, in combination with a one piece cup-

shaped inclosing casing having its open end turned toward and secured to a suitable support, a clock movement located in the casing and having its face end also turned toward the fixed support, a ring or washer-shaped member secured to the movement and located adjacent the open end and adjacent the inner surface of the casing, a disk located within the ring member and driven by the clock train and supporting a graduated dial for recording purposes and bearing on the washer shaped member, means for perforating the graduated dial, comprising a spring actuated rod passing through and supported by the clock movement and extending to the rear or closed side of the casing to afford access for operation, and means comprising a perforated plate to receive the end of the dial perforating rod to disengage the rod from the dial after perforation and on its rearward movement to normal position.

WALTER J. TIDD.
